tion of Delaware

Application February 25, 1933, Serial No. 658,654

3 Claims. (Cl. 161—18)

This invention relates to a device for measuring the speed of a golf ball, especially for the precise comparison of speeds attained by successive strokes. The object of such a device is to provide a means for instructing players in a convincing fashion as to what sort of stroke will produce the highest ball speed which in turn means the longest drive, other things being equal. It is well known among golfers that bad results are likely to follow when a player makes a strenuous effort to hit a ball harder than he can do with a relatively effortless swing. Most golfers admit the truth of this but paradoxically many of them cannot seem to believe it. This peculiarity appears to be something that is just the opposite of the humorous definition of the word "faith" as meaning "believing what you know ain't so". That is, the golfers know that pressing is usually accompanied by inferior results but they fail to believe that the best results can be obtained with relatively little effort properly applied. The average golfer who is fortunate enough to hit a number of drives cleanly and well will begin to say to himself "now that I am hitting them right I will put a little more 'beef' into it and get a 'whale' of a drive". When he does this, however, his game will probably go to pieces. Therefore, the object of this invention is to provide a mechanism for use by the professional in connection with his teaching work which will enable him to demonstrate to the pupil that the properly executed and relatively effortless stroke actually produces a greater ball speed than strokes involving great conscious exertion even when the ball is squarely hit with one of these strokes. Of course, it is possible for a golfer to come to the same conclusions as a result of driving a large number of balls from the tee, but in this case it is difficult to tell which of the balls really starts the fastest as the distance travelled depends considerably upon the nature of the soil where the ball hits and the trajectory etc. so that only by observing the average results of a number of strokes can any conclusions be reached. In contrast to this the present invention requires only a single well hit shot to establish a value of ball speed which can be obtained with a proper stroke and then the player need only make one well hit shot involving great conscious effort to demonstrate that no greater speed can be attained.

It is an object of the present invention to produce a mechanism which will be fully automatic to indicate visually a reading indicative of the ball speed and retaining the reading for as great

a length of time as desired, the reading being erased before the next operation of the apparatus by a manually controlled button.

It is another object of the invention to produce a mechanism which will be fully automatic in that a number of strokes may be made in rapid succession without any attention or adjustment to the recording means, the speed of the ball at each stroke being indicated for sufficient length of time to be observed, the indication, however, not occurring until two or three seconds after the ball is struck so as to allow the stroke to be completed at leisure before the attention is transferred to the indicating means, after which the entire mechanism of its own accord reverts to its original condition and is ready to indicate the speed of the next ball struck without any adjustment or resetting of any of its parts. Preferably, the device of this invention is to be used in connection with one of the automatic teeing machines at present on the market, which machines include a hopper to hold a large number of balls and a trigger arrangement, the actuation of which, releases one ball and allows it to roll out of the machine and into position on a rubber tee of suitable height for driving. With this preferred combination the pupil may strike ball after ball with the minimum of interruption between shots and thus retain in his mind the "feel" of each stroke together with the resulting ball speed and hence rapidly learn the proper "feel" for the best results.

In the drawing,

Fig. 1 illustrates schematically one embodiment of the present invention utilizing thyratrons to control the charging of a condenser arrangement;

Fig. 2 illustrates another modification of the invention which is entirely automatic; and,

Fig. 3 is another modification of the invention wherein the circuits are somewhat simplified.

Referring particularly to Fig. 1 there is shown a player 1 about to drive off. As pictured, the player is about to swing his club 3 and hit the teed ball 2 against the screen 20, the path of the ball is shown by the dotted lines. A microphone 4 connected to the usual microphone circuit comprising a source of current 5 and the primary of an audio transformer 6, is located adjacent the teed ball 2. The microphone is preferably provided with a reflector which concentrates sound from the impact between the club and the ball at the microphone. A similar microphone 17 connected to the usual microphone circuit comprising current source 22 and primary of

ansformer 23 is located preferably directly behind the screen 20. A pair of "thyatron" tubes and 18 having input and output circuits are ranged so as to be respectively affected by the microphones 4 and 17. The input circuit of "thyatron" 8 comprises a variable biasing source and the secondary of transformer 6 while the output circuit of "thyatron" 18 includes variable biasing source 21 and the secondary of transformer 23. The output circuits of both the "thyatrons" include a common portion comprising anode current source 9, switch 27, resistances 15 and 19 and solenoid 11. Solenoid 11 is arranged to operate a switch 12, the closure of which completes a circuit comprising condenser 13, current source 15 and resistance 16. An electrostatic voltmeter 14 is shunted across condenser 13 for giving an indication of the charge the condenser. A condenser discharging circuit is provided which includes the normally open switch 26 and resistance 24. A spring controlled sh-button 25 is arranged to cooperate with switches 27 and 26. Depressing the push-button opens switch 27 and closes switch 26 for purposes hereinafter pointed out.

The operation of the system shown in Fig. 1 as follows:—

Microphone 4 which, as previously stated, is located preferably close to the ball 2, responds to the sound emitted when the club 3 comes in contact with the ball. The sudden change in microphone current will (if the polarity of the transformer 6 is correct) kick the grid of "thyatron" 8 in a positive direction and thus start current through this "thyatron". Part of this current flows through solenoid 11 and thus closes contact 12 owing condenser 13 to charge through resistance 16. About a 20th of a second later the sound of the ball 2 hitting the screen 20 similarly starts "thyatron" 18 and thus neutralizes the current through the solenoid 11 and switch 12 opens by means of gravity or a suitable spring. (If the relay is polarized the second "thyatron" current can be arranged to have a greater effect than the first so that the magnet pull reverses in direction when the second "thyatron" starts.) Resistance 16 has capacity 13 is chosen so as to have a time constant which is approximately equal to $\frac{1}{5}$ of a second so that the voltage to which 13 is charged will be approximately proportional to the time of flight of the ball and is indicated by electro-static voltmeter 14. After the reading of 14 has been noted the machine is restored to its original condition by pressing button 25 which charges condenser 13 in a non-oscillatory fashion through resistance 24 and also breaks the plate circuits of the two "thyatrons" 8 and 18 so as to stop the "thyatron" currents. The system is then in condition for another drive. It should be understood that if necessary suitable amplifiers may be provided between the two microphone output circuits and the associated "thyatron" input circuits.

In Fig. 2, the system up to the transformers 6 and 23 is the same as described above in connection with Fig. 1. The secondary of the transformer 6 forms part of the input circuit of an amplifier 29 which is identified as amplifier No.

The output of the amplifier 29 includes the secondary of transformer 30, the secondary of which forms part of the input circuit of the tubes 33 and 37. These two tubes are connected with their respective circuits arranged so as to form a push-pull rectifier arrangement wherein grid condensers 33 and 32 are provided in combination

with the respective leak resistors 34 and 38, the output of the devices 35 and 37 includes the source of space current 36 and the coil of a solenoid 39.

The output of the microphone 17 is transferred to the input of amplifier 28 which is characterized in the drawing as amplifier No. 2. The output of amplifier 28 is coupled to the input of a second push-pull detector arrangement through the transformer 31. This second push-pull detector arrangement comprises a pair of tubes 53, 54 with their respective grid condensers 58 and 57 and leak resistors 55 and 56 respectively. The common output circuit of the tubes 53 and 54 comprises a source of space current 52 and the coil of a solenoid 47. Solenoid 39 which is in the output of the first push-pull detector circuit is arranged so as to operate the spring control switch 51, the latter is adapted to cooperate either with a stop 40 or a contact clip 41. The solenoid 47 is arranged so as to control the switch blade 50 which in turn is provided with a spring 46. Cooperating with the blade 50 are two contacts 49 and 48. A connection is provided between the switch blade 50 and contact 41 which includes a resistance 45 and a condenser 44 in series. A conductive connection is provided between the contact 48 and contact 41. Between the contact 49 and the switch blade 51 are connected in series a source of current 42 and a ballistic galvanometer 43. The operation of the system shown in Fig. 2 is as follows:—

Sound arriving at the microphone 4 due to the impact of the club 3 on the ball 2 is amplified if necessary by means of the amplifier 29, the output of which is impressed upon the push-pull rectifier tubes 35 and 37. The values of the grid condensers 33 and 32 and the leak resistors 34 and 38 are so chosen that immediately upon voltage being impressed upon the input of the two rectifier tubes the grid potential becomes negative and remains negative for an interval of time of the order of magnitude of a 10th of a second, whereby the current through the winding of solenoid 39, which as previously stated is in the output of the tubes 35 and 37, is of an abnormally low value for a 10th of a second or so.

Immediately upon the dropping of the current through winding 39 the armature 51 is drawn away from back-stop 40 by the action of the spring and over against contact 41 thus closing a circuit through ballistic galvanometer 43, contact 49, armature 50, high resistance 45, large condenser 44, contact 41, armature 51 and the battery 42.

About a twentieth of a second after the ball has been struck, however, it hits a screen 20 and the resulting sound is picked up by microphone 17, amplified if necessary by amplifier 28 and impressed upon the input circuit of the push-pull pair of rectifiers 53, 54. Grid condensers 57, 58 and leak resistors 56, 55 have values such that a current through solenoid 47 will remain abnormally small for a period of considerably more than a tenth of a second say in the order of several seconds. As soon as the current through 47 is diminished, spring 46 pulls armature 50 away from contact 49 and over against contact 48. By pulling this armature away from contact 49 the circuit through the galvanometer 43 is opened and thus current has only been allowed to flow through the galvanometer during the interval between the striking of the ball 2 and the ball striking the screen 20, although it is not essential that this interval be exactly the same as the time of flight of the ball because any additive

constant due to sluggishness in the rectifiers or time of travel of sound to the microphones will not affect relative values of resulting speed but only the absolute values. The ballistic galvanometer 43 is chosen to have a rather slow period so that its deflection which is determined by the length of time during which the circuit is complete, will not reach its maximum value until 2 or 3 seconds after the ball has been struck. It will be noted that the contact of armature 50 against point 48 discharges condenser 44 and thus prepares the condenser for the next cycle of operation. As described previously, the armature 51 will fall back into its normal open circuit position before the armature 50 falls back into its normal position so that there will be no secondary charging of condenser 44. Thus, stroke after stroke may be played within a few seconds of each other without any attention to the mechanism.

Figure 3 shows a somewhat simplified modification of the device of Figure 2. The difference in this case consists in using a single rectifier tube in combination with each microphone and connecting a single relay winding differentially to the plates of these two tubes each of which is fed with direct current through a high impedance.

In Figure 3, the system shown is similar to the system of Figure 2 up to and including the transformers 30 and 31. The output of amplifier 28 feeds into the input of rectifier tube 63 through the coupling transformer 31. The input of tube 63 includes the grid condenser 59 and the leak resistor 62. The output of amplifier 29 feeds into the input of rectifier tube 64 through the coupling transformer 30. The input of tube 64 comprises grid condenser 60 and leak resistor 61. Tubes 63 and 64 are arranged so as to have a common output circuit which comprises a source of space current 16, resistors 65 and 66 and solenoid 69 the latter being energized by the plate currents. Solenoid 69 is adapted to control a movable switch blade 75, said switch blade is normally adapted to cooperate with a contact 67 through the pull of spring 70. A second contact 68 is provided to cooperate with the blade 75 when the solenoid 69 is energized. The two contacts 67 and 68 are connected to each other through a galvanometer 71 and a source of current 72 in series while the blade 75 is permanently connected to one side of the source 72 through a series arrangement of condenser 73 and resistance 74.

The system shown in Fig. 3 operates as follows:

The relay armature 75 is normally held against point 67 by means of spring 70. When the impulse arrives from amplifier 29 the balance of the two rectifiers is upset and current flows through winding of 69 in such direction as to pull armature 75 over against contact 68 thus starting current to flow through galvanometer 71. When the impulse from amplifier 28 arrives, however, the current through winding 69 is neutralized or reversed in direction thus allowing armature 75 to be pulled back against point 67 thus interrupting the galvanometer circuit at the end of the proper interval and also discharging condenser 73.

It should be understood that the systems disclosed herein and those falling fairly within the scope of the appended claims are not limited to indicating the speed of golf balls and the like but

also include the determination of the speed of any moving body, or the measurement of any time intervals of suitable order of magnitude whose limits are capable of being indicated by electrical impulses.

I claim:

1. In an internal measuring device, a pick-up means responsive to energy waves, a circuit including at least one electronic device coupled to the pick-up means, a relay associated with said circuit, a condenser, a charging circuit for said condenser, means controlled by the relay for initiating a charging action on the condenser, a second pick-up means responsive to energy waves, a circuit including at least one electronic device coupled to the last named pick-up means, a relay associated with the last named circuit, means controlled by said last named relay for stopping the charging action on said condenser and discharging the same and means for indicating the extent of the charge placed on the condenser comprising a ballistic galvanometer having a relatively slow period connected in the condenser charging circuit and adapted to measure the extent of the charge placed on the condenser.

2. In a small interval measuring device which device may be utilized for the purpose of determining the velocity of a moving mass between two predetermined observation planes, a pick-up means, a circuit including at least one electronic device coupled to the pick-up means, a relay device connected in said circuit, a condenser, a charging circuit for the condenser, means controlled by the relay device acting upon operation to initiate a charging action on the condenser, a second pick-up means, a circuit including at least one electronic device coupled to the second pick-up means, a relay device connected in the last named circuit, means controlled by the last named relay device for stopping the charging action on the condenser and for immediately subsequently thereafter discharging the condenser means for measuring the charge in the condenser said electronic devices being so arranged as to restore said relay devices to their original condition after a time interval which is long as compared to the time interval to be measured.

3. In a small interval measuring device adapted to be utilized for determining the velocity of a moving mass between two predetermined observation planes, a pickup means, a circuit including at least one electronic device coupled to the pickup means, a relay device connected in said circuit, a condenser, a charging circuit for the condenser, means controlled by the relay device for initiating a charging action on the condenser, a second pickup means, a circuit including at least one electronic device coupled to said second pickup means, a relay device connected in the last named circuit, indicating means for measuring the charge placed on the condenser means controlled by the last named relay means for simultaneously stopping the charging action on the condenser and discharging the same, said indicating means having a comparatively slow period whereby the charge placed on the condenser is indicated by the indicating means after discharge of the condenser.

WALTER VAN B. ROBERTS.
